UNITED STATES PATENT OFFICE.

NATHAN KASDAN, OF NEW YORK, AND RICHARD F. LANDWEHR, OF WOODSIDE, NEW YORK, ASSIGNORS TO MAJESTIC METAL SPECIALTIES, INC., OF NEW YORK, N. Y., A CORPORATION OF NEW YORK.

COSMETIC-PENCIL CONTAINER.

Application filed August 6, 1928. Serial No. 297,707.

Our invention relates to cosmetic-pencil containers and refers particularly to devices of that character so constructed that the opening of the container will automatically extend a desired amount of cosmetic-pencil.

As cosmetic-pencils are composed of a soft highly colored paste or plastic material it is essential that they be completely covered and protected when in use, and that they may be employed in such a manner that the fingers of the user will not come into contact with the pencil.

It has been found that the most effective method of accomplishing the above desirable results is to have the cosmetic-pencil longitudinally movable within a casing open at one end with means for extending the pencil from, and withdrawing it into, the casing.

In order to protect the pencil when it is within the casing, it is necessary to have a lid, or cover, for the open end of the casing, which must be removed before the pencil can be extended for use.

Two operations are necessary in the employment of the present known devices, first the cover must be removed and then by a separate mechanism, or means, the pencil must be extended beyond the casing, and the two movements must be reversed in withdrawing the pencil and closing the casing.

The device of our invention possesses the valuable feature of combining these two steps of operation into one step and whereby the opening and closing of the casing automatically extends and withdraws the cosmetic-stick.

The above-mentioned, and other, novel features of our device will be evident upon a consideration of our specification and its accompanying drawings.

In the accompanying drawings illustrating one form of the device of our invention similar parts are designated by similar numerals.

Figure 1 is a perspective view of one form of the device of our invention in closed position.

Figure 2 is a side view of the device of Figure 1 in open position.

Figure 3 is an end view of Figure 2.

Figure 4 is a section through the line 4-4 of Figure 1.

Figure 5 is a section through the line 5-5 of Figure 3.

Figure 6 is a section through the line 6-6 of Figure 5.

Figure 7 is a front view of one casing member.

Figure 8 is a front view of the other casing member.

Figure 9 is a side view of Figure 8.

Figure 10 is a side view of the interior moving mechanism of the illustrated device.

Figure 11 is a section through the line 11-11 of Figure 10.

Figure 12 is a perspective view of the operating member.

The particular form of the device of our invention shown in the accompanying drawings comprises a casing formed of two members, one of which has the back 15, and the ends 16 and 17 forming the annular bottom 18. The side 15 has the arc-shaped opening, or cam-way 19 and the annular hole 20. The opposite face of the back 15 carries the finger grip plate 21.

The other casing member comprises the front plate 22 having the longitudinal flange 23 with the extended lip 24 and the longitudinal flange 25 with the extended lip 26 and the spring-guide 27. The front 22 has the arc-shaped opening or cam-way, 28 and the annular hole 29. The opposite face of the front 22 carries the finger-grip plate 30.

Positioned within the casing, assembled from the above described members, is a cylindrical spring holder 31 having the two annular holes 32 and 33.

When thus assembled the holes 20, 29 and 32 are in alignment and the arc-shaped openings 19 and 28 and the hole 33 are in alignment.

One end of the flat spring, or resilient member, 34 is fixedly attached to the spring holder 31 and the other ends carries a cosmetic-pencil holder 35 which carries the cosmetic-pencil 36.

The operating arm, or member, which also acts as a cover for the other end of the cas-

ing when the device is in closed position, comprises a U-shaped member having the two sides 37, 37 and the cover 38, preferably made from one piece of metal. The sides 37, 37 have the annular holes 39, 39 in alignment with each other and the annular holes 40, 40 in alignment with each other.

A pin, or bolt, 41 passes through the holes 39, 29, 20 and 39 and a pin, or bolt 42 passes through the hole 40, the arc-shaped opening 19, the hole 33, the arc-shaped opening 28 and the hole 40.

The operation of the device is as follows:—

Figure 1 represents the device in closed position, the cosmetic pencil 36 having been withdrawn into the device and the open end of the casing being covered by the cover portion 38 of the operating member. In order to present the pencil 36 for use, the operating member is revolved upon the pivot 41, thus causing the pin 42 to move within the arc-shaped openings 19 and 28, this cam-movement causing the spring-holder 31 to revolve upon the pin 41, forcing the spring 34, the pencil-carrier 35 and the pencil 36 upwardly, thus exposing the pencil 36 for use.

A reverse movement of the operating member causes the spring 34 to be drawn downwardly and around the spring holder 31 thus withdrawing the pencil 36, the complete movement of the operating arm causing the member 38 to cover the open end of the casing.

It will thus be seen that the cam-movement caused by the movement of the operating member either opens the device and extends the pencil, or withdraws the pencil and closes the device.

Our invention, therefore, presents a device of the character described in which the cosmetic pencil is protected when the device is in closed position and in which any desired length of pencil will be disclosed by simply opening the device by moving the operating member.

We do not limit ourselves to the particular size, shape, number, arrangement or material of parts as shown and described as these are given simply as a means for clearly describing our invention.

What we claim is:—

1. In a cosmetic pencil container, in combination, a casing, a revoluble spring holder within the casing, a resilient member attached to said spring holder and capable of being wrapped thereon, a pencil holder carried by the free end of said resilient member, an operating arm exterior of the casing and means whereby a movement of the operating arm will revolve the spring holder and move the pencil holder vertically within the casing.

2. In a cosmetic pencil container, in com-

bination, a casing, a revoluble cylindrical spring holder within the casing, a resilient member attached to said spring holder and capable of being wrapped thereon, a pencil holder carried by the free end of said resilient member, an operating arm exterior of the casing and cam means whereby a movement of the operating arm will revolve the spring holder and move the pencil holder vertically within the casing.

3. In a cosmetic pencil container, in combination, a casing having an open end, a revoluble spring holder within the casing, a resilient member attached to said spring holder and capable of being wrapped thereon, a pencil holder carried by the free end of said resilient member, an operating arm exterior of the casing having a closure for the casing and means whereby a movement of the operating arm will revolve the spring holder and move the pencil holder vertically within the casing and close the casing.

4. In a cosmetic pencil container, in combination, a casing having an open end, a revoluble cylindrical spring holder within the casing, a resilient member attached to said spring holder and capable of being wrapped thereon, a pencil holder carried by the free end of said resilient member, an operating arm exterior of the casing having a closure for the casing and cam means whereby a movement of the operating arm will revolve the spring holder and move the pencil holder vertically within the casing and close the casing.

5. In a cosmetic pencil container, in combination, a casing open at the top and having aligned arc-shaped openings and aligned centrally positioned openings in the lower portion of two sides; a revoluble cylindrical spring holder within the casing having one side closed and having an annular opening aligned with the casing central openings and an annular opening aligned with the casing arc-shaped openings; a resilient member attached to said spring holder; a pencil holder carried by the free end of the resilient member; an operating arm exterior of the casing having openings aligned with the spring holder openings; a pivotal pin passing through the central openings of the operating arm, spring holder and casing; and a pin passing through the arc-shaped openings and its aligned openings in the casing and spring holder.

6. In a cosmetic pencil container, in combination, a casing open at the top and having aligned arc-shaped openings and aligned centrally positioned openings in the lower portion of two sides; a revoluble cylindrical spring holder within the casing having one side closed and having an annular opening aligned with the casing central openings and an annular opening aligned with the casing arc-shaped openings; a resilient member

attached to said spring holder; a pencil holder carried by the free end of the resilient member; an operating arm exterior of the casing having a cover capable of closing 5 the casing opening and having openings aligned with the spring holder openings; a pivotal pin passing through the central openings of the operating arm, spring holder and casing; and a pin passing through 10 the arc-shaped openings and its aligned openings in the casing and spring holder.

7. In a cosmetic pencil container, in combination, a casing open at the top and having aligned arc-shaped openings and aligned 15 centrally positioned openings in the lower portion of two sides; a revoluble cylindrical spring holder within the casing having one side closed and having an annular opening aligned with the casing central openings and 20 an annular opening aligned with the casing arc-shaped openings; a resilient member attached to said spring holder; a pencil holder carried by the free end of the resilient member; an operating arm exterior of the casing having a cover capable of closing the casing opening and having openings aligned with the spring holder openings; a pivotal pin 25 passing through the central openings of the operating arm, spring holder and casing; and a pin passing through the arc-shaped openings and its aligned openings in the casing and spring holder the movement of the operating arm causing a vertical movement of 30 the pencil holder within the casing and closing the casing opening.

operating arm causing a vertical movement of the pencil holder within the casing.

8. In a cosmetic pencil container, in combination, a casing open at the top and having aligned arc-shaped openings and aligned centrally positioned openings in the lower portion of two sides; a revoluble cylindrical spring holder within the casing having one side closed and having an annular opening 35 aligned with the casing central openings and an annular opening aligned with the casing arc-shaped openings; a resilient member attached to said spring holder; a pencil holder carried by the free end of the resilient member; an operating arm exterior of the casing having a cover capable of closing the casing opening and having openings aligned with the spring holder openings; a pivotal pin 40 passing through the central openings of the operating arm, spring holder and casing; and a pin passing through the arc-shaped openings and its aligned openings in the casing and spring holder the movement of the operating arm causing a vertical movement of 45 the pencil holder within the casing and closing the casing opening.

Signed at New York city in the county of New York and State of New York this 4th day of August, 1928.

NATHAN KASDAN.
